UNITED STATES PATENT OFFICE

EDSON L. BENNETT, OF HUDSON, NEW YORK

FLORIST'S PICK

Application filed May 15, 1929. Serial No. 363,331.

This invention relates to devices commonly known as florists' picks, the primary object of the invention being to provide a device of this character which may be readily forced into a wreath or form on which a wreath is made so that the leaf supported by the pick will be firmly held in position, eliminating any possibility of the leaf tipping to spoil the appearance of the wreath.

Another object of the invention is to provide a pick of this character which will be hollow to the end that water may find its way to the stem of the leaf, when natural flowers or leaves are supported by the pick.

A further object of the invention is to provide a pick constructed of a length of sheet metal which is bent around the stem of a leaf or flower with which the pick is used, supporting the stem throughout the entire length of the stem.

A still further object of the invention is to provide an inwardly extended flange formed on the body portion of the pick, which flange bites into the stem forced into the pick, to securely lock the stem within the pick.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is an elevational view of a florist's pick constructed in accordance with the invention, and showing a leaf as positioned therein.

Figure 2 is a side elevational view of a pick constructed in accordance with the invention.

Figure 3 is a sectional view taken on line 3-3 of Figure 2.

Figure 4 is a sectional view taken on line 4-4 of Figure 2.

Figure 5 is a plan view of the blank from which the pick is constructed.

Referring to the drawing in detail the device comprises a body portion formed preferably of a length of thin sheet metal such as tin or the like, the same being provided with an arrow shaped head 5 defining points or spurs 6, for purposes to be hereinafter more fully described.

The body portion being constructed of thin sheet metal material is capable of being bent around the stem of a leaf or flower, in a manner as shown by Figure 1 of the drawing, to firmly secure the stem within the body portion of the pick. One edge of the body portion extends inwardly as at 7 defining a projection to bite into the stem of the leaf or flower positioned therein, to further insure against displacement of the leaf or flower from the pick.

From the foregoing it will be seen that leaves or flowers held in picks constructed in accordance with this invention, may be forced into wreaths or forms of which wreaths are constructed and they will be securely held in position by the spurs 6 that dig into the wreath or form, upon reverse movement of the pick. It will further be seen that the stem of the leaf or flower positioned in the pick, will be gripped throughout the length of the stem, eliminating any possibility of the leaf becoming disconnected from the pick. It will also be obvious that due to this construction, the pick may be used with natural leaves or flowers, the construction of the pick being such as to permit water to pass into the stem of the leaf or flower held by the pick.

I claim:

1. A florist's pick including a body portion formed of a length of thin sheet metal adapted to be bent around the stem of a leaf to secure the stem to the pick, a head at one end of the body portion, said head defining lateral spurs, and said body portion adapted to be forced into a supporting surface.

2. A florist's pick including a body portion formed of a length of sheet metal adapted to be bent around the stem of a

leaf to engage the stem throughout the length thereof, a head at one end of the body portion, and said head defining spurs.

In testimony that I claim the foregoing
as my own, I have hereto affixed my sig-
nature.

EDSON L. BENNETT.
